(57) **CLAIM**

The ornamental design for a reusable applicator tip, as shown and described.

DESCRIPTION

In these drawings, FIG. 1 is a front, left-side, perspective view of the design of the reusable applicator tip. The view, not shown, from the right side is a mirror image thereof. FIG. 2 is a perspective view from the left, rear of the applicator tip, the view from the right side being a mirror image thereof.

FIG. 3 is a side view of the applicator tip, the opposite side being a mirror image thereof.

FIG. 4 is a front view of the applicator tip.

FIG. 5 is a rear view of the applicator tip.

FIG. 6 is a top view thereof.

FIG. 7 is a bottom view thereof.

FIG. 8 is a view of a modification of the applicator tip design; and,

FIG. 9 is a second modification of the applicator tip design. The broken lines in the drawings depict environmental subject matter only and form no part of the claimed design.
